SPLIT PATTERN REGISTRATION CHECKING DEVICE

Ollie Fortschneider, Decatur, Ill.

Application May 25, 1953, Serial No. 357,104

10 Claims. (Cl. 33—180)

1

This invention pertains to foundry patterns, and more particularly to a device for checking the alignment or registration of pattern halves or segments on a split or matched plate pattern. Such patterns are used to form registering mold cavities in the cope and drag sections of a mold flask.

The use of matched plate patterns is old in the art and comprises a pattern plate having a pair of segments or halves of one or more patterns positioned in registration on opposite sides of such plate. In some instances each pair of pattern segments is formed integrally with the plate, and in other instances the segments of each pair are fastened in registering relationship on opposite sides of the pattern plate. The pattern segments on one side of the pattern plate must register exactly, or within predetermined limits, with their corresponding segments on the opposite side of the plate. Lacking such registration, the vertical edges of the mold cavities in the cope and drag sections of the flask will not align accurately and result in defective castings.

Devices for checking the registration of the pattern segments or halves of a split pattern or a matched plate pattern are known in the art. Known devices of this nature, however, can check only those edges of the pattern segments which can be reached, or are accessible, from an edge of the pattern plate; i. e., by these devices a check of the registration of the pattern segments can be made only by measuring from an edge of the pattern plate to those edges of the pattern segments facing such plate edge. Matched plate patterns, however, frequently comprise numerous pairs of pattern segments, the registering edges of some of which are not accessible of measurement from any edge of the pattern plate. Further, it has been found in actual practice that it takes about three hours to check the registration of the pattern segments of a split pattern by known devices.

Accordingly, it is an object of this invention to provide a device for checking the registration or alignment of the pattern segments or halves of a matched plate pattern which requires a minimum amount of time for performing a checking operation.

It is another object of this invention to provide a checking device of the type under consideration which will enable a registration check to be made of pattern segments which are not accessible of direct measurement from an edge of the pattern plate.

It is another object of this invention to pro-

2

vide a registration checking device of the type under consideration in which any edges of any pair of pattern segments may be checked for proper alignment.

5 It is a further object of this invention to provide a device of the type under consideration which is relatively simple in construction, with resulting manufacturing economies, and easy to operate.

10 Other objects and advantages of the invention will be apparent from the accompanying description and following drawings, in which:

Figure 1 is a front elevational view of a registration checking device embodying this invention and showing a matched plate pattern secured to the device in position for checking the registration of its pairs of pattern segments.

Figure 2 is an enlarged fragmentary end elevational view of the device shown in Figure 1 with the matched plate pattern removed therefrom.

Figure 3 is a plan view of the device shown in Figure 1, but with the registration checking means being moved to check the alignment of registering pattern segments adjacent an end of the pattern plate.

Figure 4 is an enlarged view, partly in vertical section, taken substantially on line 4—4 of Figure 1.

30 Figure 5 is an enlarged fragmentary detailed view corresponding to Fig. 4, but showing the operative position of the registration checking fingers.

Figure 6 is an enlarged longitudinal sectional view of the indicating finger shown in Figure 3.

Figure 7 is a fragmentary plan view of the base of the indicating finger and illustrating the measuring gauge mounted thereon.

Figure 8 is a fragmentary side elevational view of the base of the indicating finger taken from the side opposite that shown in Figure 6.

Referring to the drawings, there is shown in Figures 1, 2, and 3 a device embodying this invention for checking the registration of pairs of pattern segments positioned on opposite sides of the plate of a split pattern. The device may be mounted on an appropriate support, such as a table or bench 10 having pedestals 12 at the opposite ends thereof. An elongated slide base or bed 14, preferably of relatively massive metal construction in order to achieve rigidity, is mounted on the table pedestals 12 by means of feet 16 secured, as by screws 18, to the undersides of the slide base at its opposite ends and securely fastened, as by screws 20, to the pedestals. It will

55

be seen that the slide base 14 bridges the pedestals 12 with considerable clearance space between the underside of the slide base and the top of the table 10.

Two spaced parallel grooves 22 (Figures 2, 3, and 4) in the upper surface of the slide base 14 extend substantially the length thereof and provide a relatively wide land 24 therebetween. Along the bottom of each groove 22 and adjacent its end portions, the slide base 14 is provided with a series of longitudinally-spaced interiorly-threaded apertures 26. Two generally L-shaped pattern plate supporting blocks 28 having reinforcing end webs 30 are adapted to be secured in adjustably-spaced relation on top of the slide base 14 by screws 32 which extend through the foot portions 34 of the blocks and are threaded into the apertures 26 in the slide base. The blocks 28 have depending tongues 36 to fit the grooves 22. Both of the supporting blocks 28 are secured in alignment with one of the grooves 22 in the slide base 14, as shown in Figures 2 and 3, and it will be seen that a considerable distance exists between the vertical plane faces 38 of the upright legs 40 of the blocks and the other groove 22, so that a split pattern 42 may be disposed vertically against the vertical faces of the supporting blocks with the lower edge of the pattern plate 44 resting on the land 24 between the two grooves.

A clamping block 46 secures the edges of the pattern plate 44 to the supporting blocks 28 by means of screws 48 which have large knurled heads 50 and extend through the clamping blocks and are threaded into the corresponding supporting blocks. Preferably, each supporting block 28 has a vertical flange 52 of approximately the same thickness as a pattern plate and against which one edge of the corresponding clamping block 46 is engaged. Also, each clamping block 46 is provided with a pair of locator pins 54 which project inwardly toward the plane face 38 of the corresponding supporting block 28 between its vertical flange 52 and the clamping screw 48. The upper edge of the clamping blocks 46 may be slightly bevelled, as at 56, opposite the vertical faces 38 of the supporting blocks 28 to facilitate the insertion of a pattern plate into clamping position.

It will thus be seen that a pattern plate to be checked for registration of its pattern segments is supported in vertical position so that it will not bend under its own weight during the checking operation and thereby possibly result in inaccurate readings. It further will be seen that because of the variable spacing between the supporting blocks 28, the device is adapted to support pattern plates of various sizes. It is also evident that the two grooves 22 provide for reversal of the blocks 28, so that a pattern plate can be clamped in position from either side of the table 10.

The slide base 14 is provided with longitudinally-extending lateral flanges 58 having bevelled upper edges (Figures 2 and 4). The horizontal undersurfaces of these flanges 58 and also their bevelled edges define parallel rails or trackways, a horizontal pair 60 and an inclined pair 62. A generally U-shaped relatively massive and rigid carriage 64 is positioned beneath the slide base 14 and has upright side arms 66 provided with outwardly divergent or inclined upper edge portions 68. Bolts 70 extend through these upper edge portions 68 at the four corners of the carriage 64 and have rollers 72 secured thereon for

travel on the inclined rails 62. At a lower location and somewhat inwardly from the carriage ends, four bolts 74 extend through the upright portions of the side arms 66 of the carriage 64 and have rollers 76 secured thereon for engagement with the horizontal rails 60. Thus, the carriage 64 is mounted for travel longitudinally along the slide base 14, but is rigidly secured against lateral or vertical movement relative thereto. Preferably, all of the rollers 72 and 76 are provided with anti-friction bearings (not shown) for free and easy movement of the carriage on the base 14.

Depending from the carriage 64 on its opposite sides are two transversely-aligned bearings 78 in which a transverse shaft 80 is journaled by bushings 82. The opposite ends of the shaft 80 project outwardly beyond the carriage 64 and have a pair of parallel relatively massive rigid arms 84 and 86 rigidly secured thereto over the bushings 82 by pins 88 which extend through the arms 84 and 86, the bushings 82, and the shaft 80. If desired, the carriage 64 may be formed in two lateral parts, which are secured together by means of the shaft 80, as shown in Figure 4 of the drawings.

The arms 84 and 86 are of a length to extend to the upper edge of the highest pattern segment on a matched plate pattern to be checked by the device. On their free ends, the arms 84 and 86 are provided with clamp-type split journal bearings 90 having clamping screws 92 extending through ears 94 adjacent the edges of the splits in the bearings. Mounted in the bearing 90 on the arm 84 is a cylindrical reference finger 96 having a knurled outer end 98 (Figure 3) and an inner end which tapers to a cylindrical tip portion 100. The screws 92 of the split journal bearing 90 on the arm 84 are adjusted so that the reference finger 96 may be moved axially, but without radial play, to and from the split pattern being checked. Hence, by a combination of translational movements of the carriage 64, pivotal movements of the arm 84, and axial movements of the reference finger 96, its cylindrical tip portion 100 may be brought to bear against any edge of a pattern segment. Thus, even pattern segments having complicated edge configurations, such as the valve housing pattern halves 102, may be checked by the device.

Mounted for axial and rotational movements in the bearing 90 on the arm 86 is a cylindrical indicating finger 104 which tapers to a cylindrical tip portion 106 of smaller diameter than the tip portion 100 of the reference finger 96. An enlarged circular knurled handle 108 (Figure 6) is secured on the other end of the indicating finger 104, as by a set screw 110. Both arms 84 and 86 are identical in construction and secured to the transverse shaft 80 so that their split bearings 90 are in alignment. Hence, the reference finger 96 and the indicating finger 104 are maintained in rigid alignment on opposite sides of a split pattern to be checked. It also will be seen that when the tip portion 100 of the reference finger 96 is brought into engagement with an edge of a pattern segment on one side of the plate 44, the tip portion 106 of the indicating finger 104 may be brought into close adjacency with the corresponding edge of the registering pattern segment on the opposite side of the plate 44.

The indicating finger 104 is provided with a relatively-deep longitudinal groove or slot 112 (Figure 6) extending from the tip portion 106

almost to the handle 108. A relatively-short feeler lever 114 is mounted in the groove 112 adjacent the tip portion 106 of the indicating finger 104 by a pivot pin 116 extending transversely through the side walls of the groove. The lever 114 is spaced from the bottom of the groove 112 so that slight rocking movements can be imparted to the lever. The outer end of the lever 114 is substantially flush with the end of the tip portion 106 and has a feeler 118 thereon which projects radially out of the slot 112 and beyond the peripheral outline of the tip portion 100 of the reference finger 96. The outer end of the feeler 118 is provided with a contacting surface 120 adapted to engage against an edge of a pattern segment to be checked.

At its opposite end the feeler lever 114 is provided with a longitudinal slot or notch 122 having a rounded inner end within which fits a correspondingly-rounded ball-like end 124 of an indicating lever 126 which is mounted intermediate its ends on a pivot pin 128 extending transversely through the side walls of the slot 112. Thus, movements of the feeler 118 radially of the indicating finger 104 serve to rock the feeler lever 118 and, because of the ball and socket connection between the feeler lever and indicating lever 126, simultaneously rock the indicating lever.

The indicating finger 104 is provided with an aperture 130 which extends through the bottom of the slot 112 adjacent the other end 132 of the indicating lever 126. A conventional micrometer gauge 134 has a spring-pressed operating stem or pin 136 projecting through the aperture 130 and into engagement with the end 132 of the indicating lever 126, so that radial movements of the feeler 118 effect reciprocation of the gauge stem. The gauge 134 has a cylindrical casing 138 which is secured by a generally L-shaped bracket 140 (Figure 8) to the side of the indicating finger 104. Preferably, the bracket 140 has a pair of spaced elongated slots or apertures 142 through which fastening screws 144 project to adjustably secure the gauge 134 on the finger 104. It will be seen that by reason of this mounting the gauge 134 may be raised or lowered with respect to the finger 104 for calibration purposes. The gauge 134 also includes a rotatable pointer 146 (Figure 7) travelling over a dial 148, preferably graduated in thousandths of an inch, which is mounted in a cylindrical sleeve 150 that is rotatable with respect to the gauge casing 138.

A generally U-shaped bracket 152 has its base secured, as by screws 154, to the handle 108 of the indicating finger 104, and two screws 156 are threaded in opposition through the legs of the bracket 152 into close proximity of each other. A bracket 158 is secured to the sleeve 150 of the gauge 134 and has an arm 160 extending radially therefrom into a position between the ends of the screws 156 on the bracket 152, so that by suitable adjustment of the screws 156, the sleeve 150, and consequently the gauge dial 148, may be rotated relative to the pointer 146.

In operation of the device, the gauge 134 is first calibrated to read "zero" when a pair of pattern segments on opposite sides of a pattern plate are in perfect registration. This operation may be simply performed by placing a flat block (not shown) having a perfectly plane surface on the land 24 of the slide bed 14 beyond the plate clamps, or between such clamps with the split pattern removed. The reference finger 96 and its

arm 84 are then manipulated so that the cylindrical tip portion 100 of the reference finger rests on top of the flat surface of the block. The indicating finger 104 is then moved axially toward the reference finger 96 until the tip portion 106 of the indicating finger 104 is above the same surface of the block. The indicating finger 104 is then rotated by its handle 108 until the feeler 118 contacts the surface of the block and is in a position substantially normal thereto. The gauge 134 is then calibrated to read "zero" by an appropriate rough adjustment of the gauge casing 138 with respect to the indicating finger 104 by means of the screws 144 and by a final vernier adjustment of the dial 148 by means of the screws 156 which engage the radial arm 160 on the rotatable sleeve 150 of the gauge.

With the gauge 134 so calibrated, the device is ready for operation and, upon clamping a split pattern in place on the slide bed 14, the arms 84 and 86 and the reference finger 96 are so manipulated that the cylindrical tip 100 of the reference finger engages against an edge of a pattern segment to be checked for alignment with its corresponding segment on the opposite side of the pattern plate. The indicating finger 104 is then moved axially until its cylindrical tip 106 substantially touches the pattern plate. In this position the tip 106 will be closely adjacent the edge of the corresponding segment. The indicating finger 104 is then rotated by its handle 108 until the feeler 118 engages an edge of the corresponding segment and is in a position substantially normally to the surface of such edge. The gauge 134 is then read.

It will be seen that when the tip 106 of the reference finger 96 and the feeler 118 of the indicating finger 104 engage edge surfaces of corresponding pattern segments that are in exact registration or alignment, there will be no radial displacement of the contact edge or surface 120 of the feeler with respect to the peripheral outline of the cylindrical tip 106 of the reference finger, and the gauge 134 will read "zero." In the event, however, that the edge of the pattern segment engaged by the feeler 118 is offset outwardly or inwardly from the peripheral outline of the cylindrical tip 100 of the reference finger 96, and consequently from the edge of the segment engaged by the reference finger, the gauge 134 will not read "zero" but the pointer 146 will indicate a plus or minus reading depending upon the direction of offset of the two corresponding pattern segments.

Numerous checks or readings are then made of each pair of corresponding pattern segments on the split pattern, and, in the event that the corresponding segments of any pair are offset by more than a predetermined distance, usually a few thousandths of an inch, the pattern is usually discarded or possibly sent back to the pattern maker for reworking.

By reason of the almost universal movability of the fingers 96 and 104 in directions parallel and normal to a split pattern, it will be seen that even patterns having extremely irregular edge configurations may be checked with the utmost ease. It further will be seen that the invention provides a pattern registration checking device which is extremely accurate because of the massive and rigid construction of its parts, and yet which may be operated with extreme rapidity and facility. It further is pointed out that the device may be calibrated quickly and accurately.

It will thus be seen that the objects of this

invention have been fully and effectively accomplished. It will be realized, however, that the specific embodiment disclosed for the purpose of illustrating the principles of the invention is subject to change without departing from such principles. Therefore, this invention includes all modifications encompassed within the spirit and scope of the following claims.

I claim:

1. Apparatus for checking the registration of a pair of pattern segments on opposite sides of a pattern plate comprising: a reference finger and an indicating finger; means for carrying said fingers in rigid alignment on opposite sides of a pattern plate and normal thereto; means for mounting said carrying means and the plate for relative movement between said fingers and the plate in any direction parallel to the plate; a tip on the end of said reference finger laterally engageable with a pattern segment on one side of the plate; feeler means mounted for lateral movement on the end of said indicating finger and engageable with the other pattern segment on the other side of the plate; and means for measuring the displacement of said feeler means relative to the point of engagement of said reference finger with the pattern segment on the said one side of the plate.

2. Apparatus for checking the registration of a pair of pattern segments on opposite sides of a pattern plate comprising: a reference finger and an indicating finger; means for carrying said fingers in rigid axial alignment on opposite sides of a pattern plate and normal thereto; means for mounting said carrying means and the plate for relative movement between said fingers and the plate in any direction parallel to the plate; a circular tip on the end of said reference finger engageable with an edge of a pattern segment on one side of the plate; a feeler mounted for radial movement on the end of said indicating finger and engageable with a corresponding edge of the other pattern segment on the other side of the plate; and means for measuring the radial displacement of said feeler relative to the peripheral outline of said circular tip.

3. The structure defined in claim 2 wherein the indicating finger is mounted on the carrying means for rotation about the axis of said finger.

4. The structure defined in claim 2 wherein both fingers are mounted on the carrying means for movement normal to the plate.

5. The structure defined in claim 2 in which the measuring means includes: lever means within the indicating finger connected to the feeler for movement thereby; and gauge means mounted on said indicating finger for measuring movements of said lever means.

6. The structure defined in claim 5 including means for calibrating said gauge means to a zero indication when the feeler is aligned with the peripheral outline of the circular tip.

7. Apparatus for checking the registration of a pair of pattern segments on opposite sides of a pattern plate comprising: means for fixedly supporting a pattern plate; a pair of rigidly connected spaced parallel arms adapted to be positioned on opposite sides of the plate; means mounting said arms for pivotal and translational movements in directions parallel to the plate; a refer-

ence finger and indicating finger carried in rigid axial alignment by said arms on opposite sides of the plate; a circular tip on the end of said reference finger engageable with an edge of a pattern segment on one side of the plate; a radial feeler mounted for radial movement on the end of said indicating finger, said feeler normally projecting beyond the peripheral outline of said circular tip and engageable with a corresponding edge of the other pattern segment on the other side of the plate; and means for measuring the radial displacement of said feeler relative to the peripheral outline of said circular tip.

8. The structure defined in claim 7 in which the plate supporting means includes horizontally spaced clamps for engaging opposite edge portions of the plate and supporting the latter in a vertical position, and the arm mounting means includes horizontal rails extending parallel to the plate on opposite sides and adjacent the lower edge thereof and a carriage running on said rails and mounting said arms for pivotal movement about a horizontal axis transverse to said rails and below the lower edge of the plate.

9. Apparatus for checking the registration of a pair of pattern segments on opposite sides of a pattern plate comprising: means for fixedly supporting a pattern plate; a reference finger and an indicating finger; means carrying said fingers in rigid axial alignment on opposite sides of the plate and for movement in directions parallel to the plate, each of said fingers being movable normal to the plate and said indicating finger being rotatable about its axis; a circular tip on the end of said reference finger engageable with an edge of a pattern segment on one side of the plate; a circular tip of smaller diameter than said reference finger tip on the end of said indicating finger, means defining a longitudinal slot in said indicating finger tip; a feeler lever mounted in said slot for pivotal movement about an axis transverse to said slot; a feeler on the end of said lever projecting out of said slot for engagement with a corresponding edge of the other pattern segment on the other side of the plate; lever means mounted within said indicating finger and connected to said feeler lever for movement thereby; and gauge means mounted on the base of said indicating finger and engaged with said lever means for indicating radial displacement of said feeler relative to the peripheral outline of said reference finger tip.

10. The structure defined in claim 9 in which the gauge means includes a casing, an axially movable pin projecting from the casing, and spring means urging said pin into engagement with the lever means.
